UNITED STATES PATENT OFFICE.

JACOB H. BUSS, OF SALTILLO, TENNESSEE.

FLYING-MACHINE.

968,120.

Specification of Letters Patent. Patented Aug. 23, 1910.

Application filed July 2, 1909. Serial No. 505,725.

To all whom it may concern:

Be it known that I, JACOB H. BUSS, citizen of the United States, residing at Saltillo, in the county of Hardin and State of 5 Tennessee, have invented certain new and useful Improvements in Flying-Machines, of which the following is a specification.

This invention comprehends certain new and useful improvements in flying machines 10 of the heavier than air type, and the invention has for its object, an improved construction of flying machine of this character which embodies two or more horizontally disposed fans arranged to rotate in opposition to each other in the nature of gyroscopes so as to sustain the machine against the action of gravity, and at all times in a condition of equilibrium, the plurality of lifting fans working in opposite directions 15 preventing the suspended frame from revolving. And the invention also has for its object, a simple, durable and efficient construction of flying machine of this type which may be easily controlled by a single 20 operator and which embodies a novel and particularly advantageous arrangement of actuating gearing which may be easily adjusted to increase or decrease the speed or bring the machine to a standstill. 25 With these and other objects in view as will more fully appear as the description proceeds, the invention consists in certain constructions, arrangements and combinations of the parts that I shall hereinafter 30 fully describe and claim.

For a full understanding of the invention, reference is to be had to the following description and accompanying drawings in which:

40 Figure 1 is a side elevation of a flying machine constructed in accordance with my invention; Fig. 2 is a rear elevation thereof, parts being shown in section; Fig. 3 is a top plan view of the machine; Fig. 4 is a detail view partly in section, illustrating parts of the driving mechanism; and, Fig. 5 is an enlarged detail view of the friction disk which is arranged to drive the propeller.

The present embodiment of the invention 45 illustrated in the accompanying drawings includes an upper horizontally disposed fan 1 which may have any desired number of radially disposed blades of any desired width and length and set preferably at angles of 50 about 30° to the vertical, and a lower horizontally disposed fan 2 which may also

embody any desired number of blades of any desired size, but the blades of the lower fan are preferably set at an angle of about 45° to the vertical owing to the fact that as 60 the two fans revolve, the lower lifting fan 2 will work in a downward current of air set up by the upper lifting fan 1.

The upper fan 1 is secured to the upper end of a vertically disposed shaft 3, journaled in ball bearings, the said shaft working within the hollow shaft 4 to which the lower fan is connected, such latter shaft also working in ball bearings in a framework 5 of any desired construction and design 70 made up of relatively light and strong steel bars or rods riveted or bolted together.

The frame 5 supports two engines or motors of the internal combustion type, the same being three cylinder engines as illustrated in the drawing, designated 6 and arranged right and left as shown. The fuel supply pipes 7 of these engines lead from a common supply tank 8 for the gasoline or other liquid fuel, said tank being supported 80 on the framework by any suitable bracket.

The drive shafts 9 of the engines or motors 6 are provided at their inner ends with miter gear wheels 10 which mesh with upper and lower horizontally disposed miter 85 gear wheels 11 and 12 facing each other as shown. The gear wheel 11 is secured to the shaft 4 of the lower fan 2 so as to drive the same in one direction, while the lower gear wheel 12 is connected to the shaft 3 of the upper fan 1 so as to drive the same in the opposite direction and the revolution of the two fans in opposite directions obtaining the desired gyroscopic effect and preventing the rotation of the framework. 90

The framework 5 is provided with a forwardly projecting portion 13 the outer end of which provides a bearing for a longitudinally extending shaft 14 which carries at its forward end a propeller 15 the blades of which may be of any desired number and size. The inner end of the shaft 14 is journaled in the main portion of the framework 5 and carries a friction disk 15a which is splined thereon for a longitudinal movement effected by a shipper lever 16 and which is designed to engage the opposing faces of the gear wheels 11 and 12 which constitute friction pulleys. Obviously by moving the shipper lever 16, the disk 15 may be 100 moved inwardly or outwardly toward the centers or peripheries of the gear wheels 11 105

and 12 so as to decrease or increase the speed of the propeller shaft 14. To bring the propeller shaft 14 to a standstill, the disk 15 is moved inwardly toward the centers of the gear wheels 11 and 12 where depressions are formed in the opposing faces of said wheels.

The rearwardly extending portion 17 of the framework constitutes an operator's seat as shown, and a steering rudder 18 is pivotally connected to this portion of the framework said rudder being of any desired area. The rudder 18 is provided with a forwardly extending tiller 19, as clearly illustrated in the drawings.

15 From the foregoing description in connection with the accompanying drawings, it is believed that the operation of my improved flying machine will be obvious. When the driver or operator takes his seat in the rearwardly extending portion 17 of the framework, the engines or motors may be started by cranking from a pin 20 which projects upwardly from the wheel 11 and the machine may then be raised to the desired elevation, the forward movement being imparted to it by the propeller 15 the speed of which may be readily governed by manipulating the shipper lever 16.

It will be seen that the machine may be very easily controlled by one operator as there are only two handles to be actuated and that it will at all times maintain equilibrium owing to the gyroscopic action of the fans 1 and 2. The gear wheels 11 and 12 not only serve as drivers for the fans 1 and 2, but also as drivers for the propeller shaft 14, the arrangement being apparently a very simple one of comparatively few parts that are not liable to get out of order.

40 Having thus described the invention, what is claimed as new is:

1. A flying machine, embodying lifting fans, shafts to which said fans are connected, a framework arranged to be suspended by said fans, gear wheels connected to the respective fan shafts, said gear wheels having opposing plane faces, driving mechanism mounted in the frame work and arranged to turn said wheels in opposite directions, a propeller shaft journaled in the framework, a propeller secured to the propeller shaft at the outer end thereof, a disk splined on the inner end of the propeller shaft and

engaging the opposing plane faces of the gear wheels, and means for shifting said friction disk inwardly and outwardly toward the centers and peripheries of said gear wheels.

2. A flying machine embodying a lifting fan, a shaft to which the fan is connected, a framework in which the shaft is journaled, a gear wheel secured to said shaft, means for turning said gear wheel, a propeller shaft, a propeller secured to said shaft, the gear wheel being provided with a plane surface, and a disk splined on the propeller shaft and engaging the plane surface of the gear wheel, and means for shifting said friction disk inwardly and outwardly toward the center and periphery of said wheel.

3. A flying machine embodying lifting fans, vertical shafts to which said fans are connected, horizontally disposed gear wheels secured to the respective shafts, the gear wheels being arranged one above the other in spaced relation and formed with opposing plane surfaces, a motor drive shaft, a gear wheel secured to the motor drive shaft, a longitudinally extending propeller shaft, a propeller secured thereto, a vertically disposed friction disk splined on the rear end of the propeller shaft and contacting with the opposing plane surfaces of the gear wheels and means for shifting said friction disk inwardly and outwardly toward the centers and peripheries of the gear wheels.

4. In a flying machine, lifting devices including a horizontally disposed gear wheel, and means for rotating the same, said gear wheel being provided with a plane face and a depression at the center of said face, a propeller, a shaft carrying said propeller, a friction disk splined on said shaft and engaging the plane face of the gear wheel and a shipper lever connected to said friction disk and arranged to move the same outwardly and inwardly over the face of said gear wheel and into the depression thereof.

In testimony whereof I affix my signature in presence of two witnesses.

JACOB H. BUSS. [L.S.]
